LOUIS L. EDMUNDS, OF CROCKETT, CALIFORNIA.

DEVICE FOR APPLYING OUTLET FITTINGS TO FILTER LEAVES.

Application filed May 18, 1925. Serial No. 30,979.

This invention relates to a clamping device and particularly pertains to a means for clamping outlet fittings to filter press leaves.

In the manufacture of filter press leaves for use in connection with a certain type of filter, it is necessary to apply an outlet fitting to a leaf so that the liquid will drain off from the leaf. This fitting is formed with a pair of jaws engaging opposite sides of the leaf and being rigidly secured thereagainst while supporting an integral structure threaded to receive an outlet drain pipe, and it is the principal object of the present invention to provide simple means for applying this fitting to the assembled leaf and for clamping its jaw portions in gripping relation to the leaves.

The present invention contemplates the use of a pair of simultaneously moving clamping jaws adapted to cooperate in forcing the jaws of the outlet fitting against the opposite sides of the filter leaf and to permanently grip the leaf.

The invention is illustrated by way of example in the accompanying drawings, in which:

Fig. 1 is a view in perspective showing the operation of the present invention.

Fig. 2 is an enlarged view in transverse section through the device with which the present invention is concerned showing the manner in which the outlet fittings are acted upon.

Fig. 3 is a view in section showing the outlet fitting in the condition it is applied and further disclosing in dotted lines the position of the jaw members therefor when the fitting has been closed onto the leaf.

Fig. 4 is a fragmentary view in elevation showing the portion of the assembled filter leaf with the outlet fitting applied thereto.

Referring more particularly to the drawings, 10 indicates a suitable rigid support upon which are mounted bearing blocks 11 and 12. The upper block 11 is fastened to the support by suitable eye bolts 13 and 14, while the lower block 12 is rigidly secured in position relative to the support by clamping bolts 15.

The lower block 12 carries a pair of pivoted jaws 17 and 18. These jaws are mounted on a pivot pin 19 carried by the block 12 which permits the jaws to swing toward and

away from each other while being vertically suspended.

As shown in Fig. 2 of the drawings, it will be seen that the adjacent faces of the jaws are suitably recessed to accommodate the outlet fitting 20. This fitting, as more clearly shown in Fig. 3, comprises a cylindrical portion which is internally threaded to receive an outlet pipe and a pair of jaws 21 and 22, the elevation of which members is more clearly shown in Fig. 4.

The fitting before being applied to the leaf has its jaws 21 and 22 spread apart, as shown by solid lines in Fig. 3, and when it has been applied the jaws are forced together as indicated by dotted lines in the same figure. The jaws 17 and 18 are provided with pressure levers 23 and 24 respectively, by which the jaws may be swung and pressure exerted. The free end of these levers are forked to receive the trunnions 25 of nuts 26 and by which nuts the levers are moved. The nuts 26 are mounted upon the opposite ends of a screw 27 and are threaded oppositely so that rotation of the screw in a single direction will cause simultaneous movement of the two nuts in opposite directions. The screw is rotatably mounted within the upper bearing member 11 and is fitted with collars 28 disposed upon opposite sides of the bearing to prevent longitudinal movement of the screw when it is rotated.

A hand wheel 29 or other suitable means is mounted on one end of the screw to bring about its rotation, and thus to provide means for applying power to the nuts, which in turn will be transferred through the levers 23 and 24 to the jaws 17 and 18 for the purpose previously explained.

In operation of the present invention, an outlet fitting of the general shape shown in Figs. 3 and 4 is disposed over the marginal edge of an assembled filter leaf, after which the edge of the filter leaf and the outlet fitting are positioned between the jaws 17 and 18 with the fitting registering with a suitably shaped recess in the working faces of the jaws, after which the hand wheel 29 may be rotated to turn the screw 27 in a suitable direction to cause the nuts 26 to move outwardly in the direction of the arrows —a— and —b—, thus simultaneously swinging the lever arms 23 and 24 in the

directions of the arrows —c— and —d—. This will swing the jaws relative to their pivot 19 and will force the jaw portions 21 and 22 of the outlet fitting inwardly against opposite sides of the assembled filter leaf to grip the same as shown in Fig. 2 of the drawings.

It will be understood that the filter leaf and the outlet fitting during this operation will be held in their proper vertical aligned position by an aligning member 31^a. The outlet fitting may then be permanently held in its gripping position by applying rivets 30 which pass through the jaw portions of the fittings and also through the filter leaf.

By reference to Fig. 2 of the drawing, it will be seen that the outlet fitting member is rigidly and temporarily held in an aligned position relative to the clamping structure by means of a center pin 31. This pin has a thread portion 32 at its lower end, which portion extends into the threaded boss 20 of the outlet fitting. A shoulder 33 on the pin abuts against the end face of the boss 20 and also against the lower face of the bearing block 12, which block carries the jaws 17 and 18. A slotted opening 34 is formed in the upper end of the pin 31 to receive a tapered key 35 which is driven into the opening and temporarily clamps the pin in a position while it extends through the block, and draws the collar 33 against the under flat face of the bearing block 12.

It will thus be evident that the outlet fitting will be held rigidly and in aligned position relative to the meeting faces of the jaws 17 and 18. This insures that irrespective of the angle at which the jaws 21 and 22 of the outlet fitting are disposed while spread, the clamping jaws 17 and 18 will force the members 21 and 22 down into parallel clamping positions on the opposite side of the leaf.

It will thus be seen that the device here disclosed, while simple in its construction and mode of operation, permits an enormous force to be easily applied to the outlet fitting, whereby it will be firmly clamped onto the filter leaf.

While I have shown the preferred form of my invention as now known to me, it is to be understood that various changes may be made in its construction without departing from the spirit of the invention as defined in the appended claims.

Having thus described my invention, what I claim and desire to secure by Letters Patent is:

1. A machine for clamping an outlet fitting to a filter leaf, said fitting having a threaded boss and spaced jaws extending coaxially from one end of the boss, said machine comprising a frame, a pair of clamping jaws carried by the frame and adapted to swing from a common pivot, operative means for moving said jaws toward and

away from each other whereby the fitting may be inserted between the jaws and the latter be actuated to force the jaws of the fitting toward each other, the adjacent faces of the clamping jaws being recessed to accommodate the boss portion of said fitting, a centering pin detachably connected to the frame and adapted to be held suspended centrally between the jaws of the machine, said pin being adapted to be threaded 75 connected to the boss of the fitting to maintain the fitting in correct alignment relative to the jaws of the machine.

2. A machine for clamping an outlet fitting to a filter leaf, said fitting having a boss and a pair of spaced jaws extending co-axially from one end thereof, said machine comprising a stationary bearing, a pair of clamping jaws pivotally connected to said bearing and adapted to swing about a common pivot, the adjacent faces of said clamping jaws being recessed to accommodate the boss portion of the fitting whereby the latter may be positioned between the clamping jaws with the boss within said recesses and the jaw portions of the fitting contiguous to the working faces of the clamping jaws, a centering pin detachably connected with the bearing and adapted to be firmly connected with the boss of the fitting to firmly hold the fitting in correct position between the jaws, and means for simultaneously operating said jaws to cause them to forcibly move in unison toward and away from each other.

3. A machine for clamping an outlet fitting to a filter leaf, said fitting having a boss and a pair of spaced jaws extending co-axially from one end thereof, said machine comprising a stationary bearing, a pair of clamping jaws pivotally connected to said bearing and adapted to swing about a common pivot, the adjacent faces of said clamping jaws being recessed to accommodate the boss portion of the fitting whereby the latter may be positioned between the clamping jaws with the boss within said recesses and the jaw portions of the fitting contiguous to the working faces of the clamping jaws, means detachably connected with the bearing and engageable with the boss of the fitting to firmly hold the fitting in correct position between the jaws, levers rigidly connected to the jaws and extending therefrom, and means connected to said levers and operative to cause them to move the jaws in unison toward and away from each other.

4. A machine for clamping an outlet fitting to a filter leaf, said fitting having a boss and a pair of spaced jaws extending co-axially from one end thereof, said machine comprising a stationary bearing, a pair of clamping jaws pivotally connected to said bearing and adapted to swing about a common pivot, the adjacent faces of said clamping jaws be-

ing recessed to accommodate the boss portion of the fitting whereby the latter may be positioned between the clamping jaws with the boss within said recesses and the jaw portions of the fitting contiguous to the working faces of the clamping jaws, a centering pin adapted to be projected through an opening in said bearing and be suspended between the jaws to engage the boss of the fitting

and firmly hold the fitting in correct position between the clamping jaws, means for detachably holding said pin in a position relatively fixed with respect to the bearing, and means for simultaneously operating said jaws to cause them to forcibly move in unison 15 toward and away from each other.

LOUIS L. EDMUNDS.
